UNITED STATES PATENT OFFICE.

CHARLES S. FOSTER, OF PAWTUCKET, RHODE ISLAND.

YARN-REEL.

SPECIFICATION forming part of Letters Patent No. 376,590, dated January 17, 1888.

Application filed May 11, 1887. Serial No. 237,830. (No model.)

To all whom it may concern:

Be it known that I, CHARLES S. FOSTER, a citizen of the United States, residing at Pawtucket, in the county of Providence and State of Rhode Island, have invented certain new and useful Improvements in Yarn-Reels; and I do hereby declare the following to be a full, clear, and exact description of the invention, such as will enable others skilled in the art to 5 to which it appertains to make and use the same, reference being had to the accompanying drawings, and to letters or figures of reference marked thereon, which form a part of this specification.

15 My invention relates to yarn-reels; and it consists, essentially, of a center wheel or spider, a loosely-mounted supplemental wheel having a toothed rim, a series of toothed arms pivoted to the center wheel and meshing with 20 the toothed wheel, and yarn-retaining spools secured to the outer or free ends of the pivoted arms, the whole combined and arranged whereby a simultaneous movement of the pivoted arms is effected.

25 The object of the present invention is to produce a superior yarn-reel of its class, by means of which the yarn or thread may be placed thereon or removed therefrom with greater facility than heretofore.

30 In my improved reel herewith the circumference thereof may be increased about fifty per cent. over the minimum circumference of the reel, the latter corresponding to the closed position of the arms.

35 An important advantage possessed by my reel is that in whatever position the pivoted arms or extensions may be adjustably secured to the center wheel or "spider" the reel is always practically balanced, thereby maintaining a uniform tension upon the unwinding yarn. By being thus balanced the centrifugal force of the revolving reel is the same throughout its circumference.

In the accompanying sheet of drawings, illustrating my invention, Figure 1 represents a front elevation of the reel complete, showing the arms extended to their limit and corresponding to the maximum diameter, said figure also showing (by dotted lines) the arms 50 in the fully-closed or folded position. Fig. 2 is a vertical transverse sectional view of the

reel. Figs. 3 and 4 represent front and side views, respectively, of one of the radially-movable pivoted arms, enlarged. Fig. 5 is a front view of a portion of the spider. Fig. 6 55 is a vertical transverse sectional view of the same, showing a manner of mounting it on the spindle or arbor; and Fig. 7 is a reduced front view of a three-arm reel provided with my improvements.

A description of the construction of the improved yarn-reel, including the manner of its operation, is as follows:

A, referring to the drawings, designates the reel as a whole.

B designates the center portion or spider, (as drawn, having six arms,) having a center hub, as 7, extending therefrom in front and mounted on a spindle, H.

C indicates a six-armed wheel, having its hub 70 bored out to freely receive the hub 7 of the wheel B. The rim of the wheel C is provided with gear-teeth t. For the purpose of reducing the weight, the rim thereof is cut away intermediate of the arms, thereby forming six 75 toothed sectors, the rear or last tooth, t, of each sector being preferably thicker than the other teeth.

C indicate spool-arms pivoted to the outer ends of the center wheel, B, each arm C, as 80 drawn, being drilled at p' to receive a screw-threaded pin, p, which is screwed into the center wheel, as clearly shown. One of said pins, however, as p', is preferably adapted to be used as a clamping-screw to retain the several spool- 85 arms in a fixed position. The inner end or center portion of each arm C is provided with a series of gear-teeth, t, adapted to intergear with those of the wheel C, just described. ¹⁹⁰ The reason of this arrangement it is obvious if the gear-wheel be turned, say, to the right, the several pivoted arms C' geared therewith will be simultaneously turned toward the left (see dotted arrow, Fig. 1) until restrained by the teeth t'. The outer end or head of each 95 arm C' is elongated axially and made concave, as at d, to receive the barrel & of a wooden spool, the latter being secured to the arm by screws s'. (See Fig. 2.) The construction of the spool, including its flanged ends h, is substantially as usual.

The manner of frictionally mounting the reel

is as follows: The outer end portion of the spindle H is reduced in diameter, as at h', the same uniting with the enlarged portion by the cone-shaped follet i, Fig. 6, the opposite end 5 being screw-threaded and provided with a nut, m, screwed thereon, having a conical end, m'. The hub of the wheel B is bored out somewhat larger than the spindle h', the bore at each end being cone-shaped to receive the 10 said cones i and m'. A nut, n, screwed to the spindle is adapted to serve as a check-nut against the outer face of the cone-nut m. By means of this arrangement the reel is not only accurately centered, but by turning the nut m 15 in the proper direction more or less frictional resistance is imparted to the reel, as desired. In the reel, as drawn, the spindle H is adjustably secured in position by a set-screw, e, mounted in the hub of a standard, E, which 20 in turn is secured to a floor or base, b.

It is obvious that the reel may be secured to a revolving shaft, although I prefer the arrangement shown as affording better facilities for adjustment and operation.

25 The operation is as follows: Assuming the reel to be mounted on a spindle or shaft, and that it be required to place a skein of yarn on the spools, the thumb-screw p² is first loosened and an arm, C', then turned in the (dotted) arrow direction, which movement likewise simultaneously operates all the other arms, thereby reducing the diameter. The skein may now be readily placed over the flanges h and onto the spools. The arms C are next simultaneously vibrated in the opposite direction until the desired radial tension is effected, when finally all the arms are secured in position by the one screw p², after which the 30 yarn may be reeled off in the arrow direction toward the right. For certain yarns, however, where the reel revolves rapidly in the opposite direction from that shown by the full-line arrow in Fig. 1, the screw p² may be dispensed with, the centrifugal force acting to 35 automatically and simultaneously throw out 40 45

all the arms C', thereby enlarging the circumference of the reel corresponding to the length of the several layers or convolutions of the skein and maintaining a substantially uniform tension on the unwinding yarn.

It is obvious that the pivoted spool-arms may be as readily simultaneously vibrated in either direction by simply turning the wheel C on its axis a short distance.

Having thus described my invention, what I 55 claim is--

1. As an improved article of manufacture, a yarn-reel consisting of a series of yarn-carrying toothed arms, a center portion having said arms pivotally mounted and secured thereto, and a loosely-mounted toothed wheel meshing with the arms and having stops, as t', for limiting the rearward movement of said toothed arms, all combined, arranged, and operating substantially as described, and for 60 65 the purpose specified.

2. A yarn-reel having a center portion adapted to revolve on its axis, a series of toothed arms adapted to carry yarn arranged around said center portion and pivoted thereto, a loosely-mounted toothed wheel engaging the several toothed arms, and a stop for limiting the angular movement of said arms and wheel, substantially as hereinbefore described.

3. The combination of the center portion or spider, B, a loosely-mounted toothed wheel, as C, having a series of stop-teeth, t', a series of toothed yarn-carrying arms, as C', pivotally mounted to the said spider B and meshing with the wheel C, and means for simultaneously securing the said arms in position after adjustment, the whole constructed, arranged, and operating substantially as shown and described, and for the purpose specified.

In testimony whereof I have affixed my signature in presence of two witnesses.

CHARLES S. FOSTER.
